United States Patent Office.

MATTHEW M. CARR, OF RINGWOOD, ILLINOIS, ASSIGNOR TO HIMSELF AND
THOMAS S. CARR, OF SAME PLACE.

Letters Patent No. 79,311, dated June 30, 1868.

IMPROVEMENT IN WAGON-BODY.

The Schedule referred to in these Letters Patent and making part of the same.

TO ALL WHOM IT MAY CONCERN:

Be it known that I, MATTHEW M. CARR, of Ringwood, in the county of McHenry, and State of Illinois, have invented a new and useful Improved Wagon-Body; and I do hereby declare the following to be a full, clear, and exact description of the same, reference being had to the accompanying drawings, and the letters and figures marked thereon, which form a part of this specification, and in which—

Figure 1 represents a side elevation of my invention.

Figure 2 an elevation of the opposite side.

Figure 3 a bottom view, and

Figure 4 a front elevation.

The nature of my invention consists in constructing a wagon-body, so that the bottom thereof, which is made in sections, can be swung down to dump the load at the will of the operator.

To enable those skilled in the art to manufacture and use my invention, I will proceed to describe the same with particularity.

The same letters of reference refer to the corresponding parts in the different figures.

A represents the ordinary side-boards of the wagon-body, and B the end-board; but the bottom is made in sections, as indicated by C, D, and E, which are hinged at one side so that they will swing down.

F represents a bar of iron or a strong wooden strip, which is pivoted at H, and serves as a latch to hold the bottom up, by latching on to the catch I. The catch I is a metallic catch attached to the side-board of the wagon, and so arranged that the spring J, placed behind one end of the latch F, holds said latch pressed into the catches I. There are levers K attached to the side of the wagon-body, which are connected with rods to the levers L, so that the operator, by vibrating the levers L, throws the levers K against the latches F, and by compressing the springs J, throws the latches off the catches, when the bottom swings down. There are levers M also near the driver's seat, which have cords or chains N attached to them, and passing through loops or over pulleys O attached to the side of the wagon-body, are so attached to the bottom of the wagon C, D, and E, that by vibrating the levers when the sections of the bottom are down, it will swing them up and fasten them, as shown in fig. 3. A single lever, L, could be used to remove all the latches F from the catches K, so that the operator, by moving a single lever, could open the bottoms to the different sections of the wagon-box, but I prefer to have a lever, L, to each section of the bottom, so that the operator can discharge a part only of the load at his pleasure, as he may desire. There also may be only one lever M with chains N, so connected therewith that the operator with it could close the different sections of the wagon-bottom.

The dotted lines P, in fig. 1, represent partition-boards, which divide the wagon-body into compartments, and the dotted lines R represent the ordinary end-boards of the wagon-body. By this division of the interior of the wagon-box into compartments, the operator by dropping one division of the bottom discharges only that part of the load contained in that one compartment of the wagon-body.

S represents the ordinary axles of a wagon, which may be constructed, so far as the running part thereof is concerned, in any known way.

Having thus fully described the construction and operation of my invention, what I claim, and desire to secure by Letters Patent, is—

The combination of the hinged sections of the bottom C D E, the bars F, pivoted as described at H, the springs J, latches I, levers K, cords or chains G and N, and levers L and M, all arranged and operating in the manner set forth.
